ABSTRACT

A wash-draw apparatus is improved by use of a multi-channeled stripping guide located in the path of yarn emerging from the liquid bath in the apparatus. The guide extends below the bath surface and includes additional yarn contacting surfaces above the surface of the bath.

FIG. 2a

FIG. 2b

FIG. 3

FLUID STRIPPING DEVICES

BACKGROUND OF THE INVENTION

This invention is concerned with the liquid treatment of moving filamentary yarns and more particularly with means to improve efficiency of sequential contacts of yarns with a plurality of liquids by more thorough stripping of a liquid from the yarn after immersion therein.

In the treatment of yarns in a multiplicity of liquid baths as, for example, in employing means to apply a reagent uniformly to the surface thereof or a means to extract a solvent therefrom, it is well known that as the speed of yarn travel increases so does the rate of carry-over of liquid from one bath to the next. In U.S. Pat. No. 3,381,506, it is shown that a yarn traveling upwardly from a water bath at about 400 ypm can carry out about eight times its weight of water. As speeds increase beyond 400 ypm, the carry-over is much greater. This greatly reduces efficiency of the operation. Further additional means must be provided to collect carry-over from the final bath in order to avoid a serious housekeeping problem.

With higher speed operations, it is also important to minimize the number and severity of contacts between wet yarn and stationary surfaces; the high friction of such contacts can be adverse to mechanical quality of the yarn.

A means involving minimal yarn contact with stationary surfaces, which minimizes liquid carry-over in processes involving treatment of yarn by immersion in one or more liquids would be highly desirable.

SUMMARY OF THE INVENTION

This invention provides novel means to reduce the quantity of liquid transported out of a bath of liquid by a moving yarn. It also provides a simple means for reducing the tendency for "twinning" of adjacent parallel yarns under the influence of a column of liquid lifted from the bath by the yarn.

These and other advantages are provided by this invention in a process for on-the-run sequential contacting of two or more filamentary strands with liquids in a plurality of baths comprising conducting the strands along separate defined paths into and out of each bath of liquid. The apparatus improvement comprises a multichanneled guide extending below the surface of the bath with each channel being in alignment with a separate defined path so the yarn passes through the channels as it moves in its path of emergence through the bath. The channels are defined by three or more substantially parallel plates, the bottoms of which are at or below the surface of the baths and oriented with their major faces lying in substantially vertical planes which intersect the plane which includes the paths of said strands, the upper surfaces of said plates being above the normal liquid level or submerged no more than one-half inch, said channels having a height of three-fourths inch to 1 inch, a width equal to one-eighth to one-sixth of their height H, and a length L that is twice their height H (FIGS. 2-3). Multichanneled stripper portion 22 is fixed in an attitude, relative to the strand path, which permits a light contact between surfaces 25a and the strands, one strand being positioned in each channel defined by a pair of adjacent plates 23.

Such liquid strippers as are provided in this invention provide several advantages over devices known in the art. They allow close positioning of individual ends and higher speed of yarn travel, thus increasing substantially the productivity of the liquid-contacting operation. It has been found that a spacing of as little as one-fourth inch between filamentary strands can be em-

BRIEF DESCRIPTION OF THE DRAWINGS

FIG. 1 is an over-all schematic cross-sectional elevation view of a multiple-bath extraction-drawing process representing one embodiment of this invention.

FIGS. 2a and 2b are front and side schematic elevation views respectively of a four-strand liquid stripper 10 such as may be employed in the process of this invention.

FIG. 3 is an enlarged perspective view of a section of stripper plate members with an associated yarn contacting surface member.

DETAILED DESCRIPTION OF THE PREFERRED EMBODIMENT

With reference to FIG. 1, filamentary strands 10 from source not shown are conducted over driven rolls 12 and idler rolls 14 which are submerged in baths of extraction liquor 16. Fresh extraction liquor is supplied to the final bath through inlet pipe 18, it flows by gravity counter to the direction of strands 10 and is removed at outlet pipe 19 for recovery of the solvent it contains. The surface speeds of driven rolls 12 increase from strand entrance to exit according to a pattern selected to provide the desired extent of drawing. Thus, the strand emerging from the final bath travels at a speed several times as fast as it does on entering the first tank.

The paths of the strands as they leave the submerged, idler rolls are diverted slightly by a liquid stripper generally designated 20 which is positioned near the surface of the liquid in each bath. Guide 20 includes a multichanneled stripper portion 22 and a ladder portion 24 connected by side members 26.

The multichanneled portion 22 shown in the drawings comprises five plates 23 in a substantially equi-spaced parallel relationship with their major faces 23a being in substantially vertical planes that intersect the plane that includes the vertical strand paths. The plates 23 are held in spaced relationship to each other by the yarn contacting surface members 25a formed on guide bar 25. The ladder portion 24 includes horizontally oriented ladder guide bars 27, 28, 29 connected between side members 26. The plates 23 and associated guide bar 25 are positioned such that the bottoms of plates 23 are at or below the liquid surface, the tops of plates 23 are above or no more than one-half inch below the liquid surface, and ladder guides 27, 28, 29 are above the surface of the liquid. Multichanneled guides 22 have been found to operate successfully with channels having a height H of three-fourths inch to 1 inch, a width equal to one-eighth to one-sixth of their height H, and a length L that is twice their height H (FIGS. 2-3). Multichanneled stripper portion 22 is fixed in an attitude, relative to the strand path, which permits a light contact between surfaces 25a and the strands, one strand being positioned in each channel defined by a pair of adjacent plates 23.

Such liquid strippers as are provided in this invention provide several advantages over devices known in the art. They allow close positioning of individual ends and higher speed of yarn travel, thus increasing substantially the productivity of the liquid-contacting operation. It has been found that a spacing of as little as one-fourth inch between filamentary strands can be em-

ployed without webbing of transported liquid into a continuous sheet. If webbing occurs, as will happen at a spacing of one-half inch or less in the absence of the stripper, carry-over can be as high as 100 parts by weight of water per part of yarn. At a spacing of one-fourth inch, using the apparatus and process of this invention, carry-over of water is typically reduced to 2 pounds water per pound of yarn with the attendant improvement in efficiency of strand-liquid contacting.

A second major advantage in the apparatus and process of this invention is in essentially complete absence of "twinning." When water webs between two running filamentary strands as they emerge from the bath, the two strands frequently are brought together or "twin." Sufficient turbulence frequently is present in the web to intertwine the filaments of two or more strands into a single bundle which will not always separate on-the-run into the original strands at the next guide. Broken filaments and discontinuities thus are the result of twining. Thus a substantial advantage of the apparatus and process of this invention is seen in improved quality of the yarn, better continuity of the process and, thereby, an over-all improvement in the economies of the operation.

What is claimed is:

1. In an apparatus for contacting a plurality of strands of yarn with a liquid wherein the strands are moved upwardly and downwardly in separate substantially vertical paths through a liquid bath, the improvement comprising: a multichanneled guide extending below the surface of said bath with each channel of said guide being in alignment with a separate path, said yarn passing through said channels as it moves upwardly, said channelled guide comprising three or more equispaced parallel plates having major faces lying in substantially vertical planes that intersect the plane that includes the vertical yarn paths, said plates being held in said spaced relationship by a plurality of substantially horizontally oriented yarn contacting surface members, said members being below the surface of said bath.

2. The apparatus as defined in claim 1, including a plurality of substantially horizontally oriented bars mounted across the upwardly moving yarn paths.

3. The apparatus as defined in claim 1, said channels having a width of from one-eighth to one-sixth of their height and a length of about twice their height.
